(57) **CLAIM**

The ornamental design for a display screen or portion thereof with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with animated graphical user interface showing the claimed design;

FIG. 2 is a second image thereof;

FIG. 3 is a front view of a display screen or portion thereof with animated graphical user interface showing the claimed design;

FIG. 4 is a second image thereof;

FIG. 5 is an enlarged view of the portion shown in dot-dash broken lines in FIG. 1, for ease of illustration;

FIG. 6 is an enlarged view of the portion shown in dot-dash broken lines in FIG. 2, for ease of illustration;

FIG. 7 is an enlarged view of the portion shown in dot-dash broken lines in FIG. 3, for ease of illustration; and,

FIG. 8 is an enlarged view of the portion shown in dot-dash broken lines in FIG. 4, for ease of illustration.

The appearance of the animated image sequentially transitions between the images shown in FIGS. 1-2, 3-4, 5-6, and 7-8, respectively. The process or period in which one image transitions to another forms no part of the claimed design. The outermost dashed broken lines in the figures show a display screen or portion thereof, and form no part of the claimed design.

The other dashed broken lines, the dot-dash broken lines, and the dot-dot-dash broken lines in the figures show boundaries that form no part of the claimed design.

The faded areas including numbers, Chinese characters, icons, and background images between the dashed broken lines and the dot-dash broken lines in the figures show
